UNITED STATES PATENT OFFICE.

RAYMOND E. CRANE, OF CAMERON, WEST VIRGINIA.

DESIGN FOR A WATER-TANK.

No. 40,188.

Specification for Design.

Patented July 27, 1909.

Application filed February 24, 1909. Serial No. 479,851. Term of patent 14 years.

To all whom it may concern:

Be it known that I, RAYMOND E. CRANE, a citizen of the United States, residing at Cameron, in the county of Marshall and State of West Virginia, have invented a new, original, and ornamental Design for Water-Tanks, of which the following is a specification, reference being had to the accompanying drawing, forming part thereof, in which—

Figure 1 is a perspective view of the tank looking from the rear; and Fig. 2 is a perspective view from the front.

The essential features of the design are the generally cylindrical body of the tank, a front wall integral with the body, an integral back, and an opening in the top of the body closed by a cover plate.

I claim:

The ornamental design for a water tank, as shown and described.

R. E. CRANE.
